UNITED STATES PATENT OFFICE.

HENRY D. MURDOCK, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS AND SYSTEM.

Application filed October 7, 1921. Serial No. 505,895.

To all whom it may concern:

Be it known that I, HENRY D. MURDOCK, a citizen of the United States, and a resident of Wilkinsburg, in the county of Allegheny and the State of Pennsylvania, have invented a new and useful Improvement in Control Apparatus and Systems, of which the following is a specification.

My invention relates to control systems and it has particular relation to control systems embodying a line switch that is governed by a controller.

One object of my invention is to provide an improved method for so controlling a line switch that it shall be closed upon the controller being actuated in one direction and opened upon the controller being actuated in another direction.

Another object of my invention is to provide a control system for so governing a line switch that it may be closed only upon the controller being actuated in a forward direction to its first operative position.

Another object of my invention is to provide means for governing a line switch that shall be simple and economical in construction and positive and reliable in operation.

Briefly speaking, my invention consists in employing a relay having a plurality of oppositely wound coils to govern the closure of a line switch, the energization of the coils of the relay device being selectively governed by means of a switching device that is associated with a master controller.

For a better understanding of my invention, reference may be made to the accompanying drawing,

Figure 1 of which is a diagrammatic view of a motor-control system embodying my invention; and

Fig. 2 is a view, in side elevation, of a portion of a controller that is illustrated in Fig. 1 of the drawing.

Referring to Figs. 1 and 2 of the drawing, a motor 1, having an armature 2 and a series field-magnet winding 3, is energized, upon the closure of a line switch 6, from a source of electrical energy, such, for example, as a trolley-wire 4, through a trolley-pole 5, the line switch or circuit-breaker 6, actuating coil of an overload trip 14, series field-magnet winding 3 and armature 2 of the motor 1 and starting resistor 7 to Ground.

The line switch 6 is provided with an actuating coil 8, the energization of which is

governed by a relay device 9 having a plurality of oppositely-wound actuating coils 11 and 12, and a controller 13. The overload trip 14 is provided for opening the line switch 6 upon the occurrence of excessive current conditions. The relay device 9 is provided with a core member 15 and a pivotally mounted armature member 16 which is biased to its open position by means of a resilient member or spring 17.

A stationary control finger 18 is adapted to be engaged by a contact member 19 that is securely mounted upon the armature member 16. The energization of the coils 11 and 12 of the relay device 9 is governed by the controller 13, which may comprise a rotatably mounted shaft 21 upon which is secured a non-conducting drum member 22 having an "Off" position and a plurality of operating positions.

A contact segment 23, which is securely mounted upon the drum 22, is electrically connected to Ground by means of a circuit comprising a conductor 24, shaft 21 and conductor 25 in accordance with a familiar practice. An arm 26, which is resiliently mounted upon a block 27 constituting part of the controller 13, is provided with a pivotally mounted member 28. The member 28, which may be actuated by frictional engagement with drum 22, engages the contact segment 23 when the controller 13 occupies its first position, which is the position illustrated in Fig. 1 of the drawing.

The pivotally mounted contact member 28 is permanently connected to the actuating coil 11 of the relay device 9. When the pivotally mounted member 28 is actuated in a clockwise direction by the drum member 22 of the controller 13, the member 28 engages a stationary contact member 29 which is permanently electrically connected to the actuating coil 12.

A pivotally mounted member 31, which is adapted to move between a plurality of stops 32 and 33, prevents the pivotally mounted contact member 28 from engaging the contact segment 23 when the drum 22 is actuated in a counter-clockwise direction toward its "Off" position.

The closure of the line switch 6 is effected by actuating the controller 13 from its "Off" position to its first position, wherein the contact segment 23 engages the pivotally mounted contact member 28, thereby estab-

lishing a circuit from the trolley-wire 4 through contact members of the overload trip 14, auxiliary resistor 34, actuating coil 8 of the line switch 6, actuating coil 11 of the relay device 9, pivotally mounted member 28, contact segment 23, conductor 24, controller shaft 21 and conductor 25 to Ground.

When the coil 11 of the relay 9 is energized, the armature member 16 thereof assumes its closed position, thereby establishing a holding circuit from the trolley-wire 4 through the contact members of the relay device 14, auxiliary control resistor 34, actuating coil 8 of the line switch 6, actuating coil 11 of the relay device 9, control fingers 18 and 19 of the relay device 9 and auxiliary control resistor 35 to Ground.

When the controller 13 is actuated beyond the first position, the contact segment 23 is no longer engaged by the control finger 28. However, the coils 8 and 11 of the line switch 6 and relay 9, respectively, are energized by the holding circuit through the control fingers 18 and 19, which has just been described.

When the controller 13 is actuated in a counter-clockwise direction, the pivotally mounted contact member 28 is actuated in a clockwise direction by its frictional engagement with the drum 22, thereby causing the contact member 28 to engage the stationary contact member 29.

Under these conditions, a circuit is established from the trolley-wire 4 through contact members of the overload relay 14, auxiliary control resistor 34, actuating coil 8 of the line switch 6, actuating coil 12 of the relay 9, stationary contact member 29, pivotally mounted contact member 28, control fingers 18 and 19 of the relay device 9 and auxiliary control resistor 35 to Ground.

When both coils 11 and 12 of the relay device 9 are energized, the relay device will be quickly opened by the armature member 16 being actuated in a counter-clockwise direction by the spring 17, as the coils 11 and 12 are oppositely wound, thereby establishing opposing magnetic fields.

When the armature member 6 of the relay device 9 assumes its open position, coil 8 of the line switch 6 and coils 11 and 12 of the relay device 9 are de-energized, as the movable control finger 19 no longer engages the stationary control finger 18. The line switch 6 will not be closed, when the controller 13 is returned to its first position, as the pivotally mounted member 31 forces the contact member 28 outwardly to prevent it from engaging the contact segment 23.

From the above description, it is apparent that, by means of a simple relay device and a switching device, which may be mounted on practically any controller, it is possible to secure effective and positive operation of

a line switch, the relay device being so designed as to insure very rapid opening of the switch, when the controller is actuated in a reverse direction.

If it is considered preferable to dispense with the relay 9, substantially the same arrangement of circuits may be obtained by providing the line switch 6 with two oppositely wound coils and an auxiliary contact member for establishing a holding circuit. 75

While I have shown my invention in a preferred form, it is apparent that other modifications may be made in the arrangement of the circuits and in the apparatus employed without departing from the spirit 80 of my invention. I desire, therefore, to be limited only by the scope of the appended claims.

I claim as my invention:

1. In a control system, the combination 85 with a translating device, of a switch for energizing said device, a controller having a plurality of operative positions, and means comprising a plurality of coils governed by said controller for closing said switch only upon said controller being actuated to its first operative position and for opening said switch upon said controller being actuated in a reverse direction.

2. In a control system, the combination 95 with a translating device, of a switch for energizing said device, a relay device for governing said switch, a controller having a plurality of operative positions, and means actuated by said controller for energizing 100 said relay.

3. In a control system, the combination 105 with a translating device, of a switch for energizing said device, a relay device having a plurality of actuating coils for governing said switch and means comprising a controller for governing the energization of 110 said coils.

4. In a control system, the combination 110 with a translating device and a switch for governing the energization of said device, of a relay device having a plurality of actuating coils for governing said switch, a controller and means actuated by said controller for selectively energizing said coils. 115

5. In a control system, the combination 120 with a translating device and a switch having an actuating coil for governing the energization of said device, of a relay device having a plurality of actuating coils for governing the energization of the coil of 125 said switch, and means comprising a controller for selectively energizing the coils of said relay device.

6. In a control system, the combination 125 with a translating device and a switch having an actuating coil for governing said device, of a relay device having a plurality of actuating coils for governing the energization 130 of the coil of said switch, a controller

- having a plurality of positions, and means associated with said controller for governing the energization of the coils of said relay device, one of said coils being energized by said means when said controller is actuated in one direction, and the other of said coils being energized by said means when said controller is actuated in the reverse direction.
10. 7. In a control system, the combination with a translating device and means comprising a switching device for governing the energization of said translating device, said switching device having a plurality of 15 coils, of a controller and means actuated by said controller for selectively energizing said coils.
8. In a control system, the combination with a translating device and means comprising a switching device for governing the energization of said translating device, said switching device having a plurality of actuating coils, of a controller and means governed by said controller for energizing one 25 of said coils upon said controller being actuated in one direction and for energizing another of said coils upon said controller being actuated in another direction.
9. In a control system, the combination 30 with a translating device and means comprising a switching device for governing the energization of said translating device, said device having a plurality of coils, of a controller having an "Off" position and means comprising a movably mounted member for governing the energization of said coils, one of said coils being energized upon 35 said member being actuated by said controller to a predetermined position and the other of said coils being energized upon 40 said member being actuated by said controller to another position.
10. In a control system, the combination with a translating device and means comprising a switching device having a plurality of coils for governing the energization of said translating device, of a controller having an "Off" position and a plurality of operating positions, and means comprising a 45 movably mounted member for selectively 50 energizing said coils, one of said coils being energized upon said controller being actuated forwardly to its first operative position and the other of said coils being energized upon said controller being actuated 55 toward the "Off" position.
11. In a control system, the combination with a translating device and a line switch having an actuating coil for governing the energization of said device, of a controller having an "Off" position and a plurality of operative positions, a relay device having a plurality of coils, means associated with said controller for energizing one of the coils of said relay and the coil of said switch only 60 upon said controller being actuated to its first operative position, means independent of said controller for maintaining said coils energized, and means comprising the other coil of said relay and said first and second 65 means for de-energizing said coils upon said controller being actuated toward its "Off" position.

In testimony whereof, I have hereunto subscribed my name this 27th day of September, 1921. 75

HENRY D. MURDOCK.
